US00D954107S

(12) **United States Design Patent** (10) Patent No.: **US D954,107 S**
(45) Date of Patent: ** Jun. 7, 2022

(54) **DISPLAY SCREEN OR PORTION THEREOF WITH ICON**

(71) Applicant: **23andMe, Inc.**, Sunnyvale, CA (US)

(72) Inventors: **Tracy Keim**, Altadena, CA (US);
Sooyun Choi, Mountain View, CA (US); **Sampo Aleksi Jalasto**, Mountain View, CA (US); **Joel Parsons**, Helsinki (FI); **Jesse Jouni Sakari Maula**, Menlo Park, CA (US)

(73) Assignee: **23andMe, Inc.**, Sunnyvale, CA (US)

(**) Term: **15 Years**

(21) Appl. No.: **29/781,970**

(22) Filed: **May 3, 2021**

Related U.S. Application Data

(62) Division of application No. 29/680,749, filed on Feb. 19, 2019, now Pat. No. Des. 921,037, which is a division of application No. 29/597,377, filed on Mar. 16, 2017, now abandoned, which is a division of application No. 29/543,031, filed on Oct. 20, 2015, now Pat. No. Des. 785,672.

(57) **CLAIM**

The ornamental design for a display screen or portion thereof with icon, as shown and described.

DESCRIPTION

The patent file contains at least one drawing executed in color. Copies of this patent with a color drawing will be provided by the office upon request and payment of the necessary fee.

The FIGURE is a front view of a display screen or portion thereof with icon showing the claimed design.

The broken lines in the FIGURE show a display screen or portion thereof, and form no part of the claimed design.

1 Claim, 1 Drawing Sheet
